UNITED STATES PATENT OFFICE.

ADOLPH M. HOLSTEIN, OF SYRACUSE, NEW YORK.

DESIGN FOR FURNITURE, CASKET, INTERIOR, OR EXTERIOR DECORATION.

52,743.

Specification for Design.

Patented Dec. 10, 1918.

Application filed August 22, 1917. Serial No. 187,549. Term of patent 3½ years.

To all whom it may concern:

Be it known that I, ADOLPH M. HOLSTEIN, a citizen of the United States, residing at Syracuse, in the county of Onondaga and State of New York, have invented a new and original and ornamental Design for Furniture, Casket, Interior, or Exterior Decoration, of which the following is a specification, reference being had to the accompanying drawing, forming a part hereof, which is a face view of the ornamental design.

The drawing is an elevation or face view of this design.

This design consists of a foliated shield in Renaissance style supported on each side by a conventional horn of plenty containing fruit, leaves and buds as shown.

I claim:

The ornamental design for furniture, casket, interior, or exterior decoration, substantially as shown and described.

In testimony whereof, I have hereunto signed my name, at Syracuse, in the county of Onondaga, and State of New York, this 29th day of June, 1917.

ADOLPH M. HOLSTEIN.
